UNITED STATES PATENT OFFICE.

CLARENCE C. LONGARD, OF HALIFAX, NOVA SCOTIA, CANADA.

INTERNAL-COMBUSTION ENGINE.

1,101,300.

Specification of Letters Patent. Patented June 23, 1914.

Application filed October 26, 1912. Serial No. 727,970.

To all whom it may concern:

Be it known that I, CLARENCE C. LONGARD, citizen of Canada, residing at Halifax, in the Province of Nova Scotia and Dominion of Canada, have invented new and useful Improvements in Internal-Combustion Engines, of which the following is a specification.

This invention relates to an internal combustion engine which operates on the two cycle principle and embodies means whereby the spent gases are forced out of the cylinder through the instrumentality of an auxiliary piston in the cylinder while the main piston uncovers the exhaust port.

The invention has for its general object to improve and simplify the construction and operation of internal combustion engines whereby the efficiency is greatly increased, a minimum number of parts employed and mechanically actuated valves eliminated.

Another object of the invention is the employment of an auxiliary piston which is pneumatically or spring-actuated at the end of the power stroke of the main piston for forcing out or displacing the spent gases, and for simultaneously sucking in the next charge of explosive mixture, while on the return stroke the auxiliary piston moves with the main piston whereby the previously drawn in charge is compressed and finally transferred to the explosion chamber between the pistons, so that upon ignition the explosive forces of the gases will impart a power impulse to the main piston, there being a power impulse imparted for each rotation of the crank shaft as in two cycle engines.

With these objects in view, and others, as will appear as the description proceeds, the invention comprises the various novel features of construction and arrangement of parts as will be more fully set forth herein-after and defined in the claim.

In the accompanying drawing which illustrates certain embodiments of the invention: Figure 1 is a central vertical section of an engine cylinder and accompanying parts for carrying out the invention. Fig. 2 is a fragmentary detail view of a modified form.

Similar reference characters are employed to designate corresponding parts in the figure.

Referring to the drawing: A designates a water jacketed or other cooled cylinder which is shown in the present instance of

uniform bore, and containing the main piston 1 and the auxiliary piston 2 that are separated by an explosion or combustion chamber 3, which chamber has a fuel admission port 4 at a point near the limit of the instroke of the piston 1, and an exhaust port 5 located in the cylinder wall at the limit of the outstroke of the piston 1. The explosive charge in the chamber 3 is fired by a suitable ignition device (not shown) mounted in the cavity 6.

Between the head 7 of the cylinder and the auxiliary piston 2, is a combined charge suction and compression chamber 8 which is provided with a port 9 through which the charge is sucked in during the down or outstroke of the auxiliary piston, and through which the charge is forced out during the up or instroke. The port 9 communicates with the valve chamber 10 which communicates with a carburetor or other mixing device through an opening or conduit 11, there being in the valve chamber 10 a puppet check valve 12 which opens toward the port 4 of the cylinder so that the charge can be transferred from the chamber 8 to the explosion chamber 3 through the port 9, valve casing 10 past the valve 12 and through the port 4. This valve 12 opens automatically under the pressure of the compressed charge in the chamber 8 at the time the pressure in the chamber 3 is approximately at atmosphere by the opening of the exhaust port 5.

Although the auxiliary piston 2 is mechanically independent of the main piston, it is prevented from coming into contact with the latter by means of a cushioning device which comprises a stem 13, centrally disposed on the auxiliary piston 2, and adapted to enter a depression or pocket 14 carried by the head 15 of the main piston. As the stem 13 enters the pocket or cylinder 14, the gas entrapped in the latter becomes compressed and serves as a cushion between the pistons, and furthermore the pistons are thus maintained a suitable distance apart, as on the up or instroke, so that a charge of gas or mixture can enter the space or chamber 3 at the proper time. A cushioning device is also provided for the auxiliary piston to withstand the shocks of the explosions exerted thereon, such device comprising a stem or plunger 16 which reciprocates in a tubular neck or extension 17, projecting outwardly from the cylinder head 7, and on the outer end of extension 17 is formed a cham-

ber 18 entirely closed to the atmosphere. At the inner portion of the neck is a port 19 that is uncovered by the stem or plunger 16 when the auxiliary piston 2 is at the end 5 of its down or instroke, and consequently air will fill the chamber 18 and neck 17 so as to be compressed during the reverse stroke of the auxiliary piston 2 and its stem 16, this compression of the air in the chamber 10 18 serving to effectually cushion the auxiliary piston. It will be noted that the port 9 is somewhat separated from the head 7, so that when the port 9 is covered by the auxiliary piston some gas or mixture will 15 be entrapped in the chamber 8 and subjected to compression, adding thereby a cushioning effect.

In describing the cycle of operation, it will be assumed that the piston 1 is at the 20 end of its power stroke with the exhaust port 5 open. During the power stroke the auxiliary piston 2 is at the limit of its upward movement, with air under compression in the chamber 18. This compressed 25 air acts on the plunger or stem 16 and quickly forces the auxiliary piston downwardly, when the exhaust port 5 is opened, thereby expelling the exhaust gases. The two pistons are prevented from coming in 30 contact by the cushioning device 13, 14. During this downward stroke of the auxiliary piston 2 the next charge is sucked into the chamber 8 through the port 9. Consequently on the in or return stroke of the 35 main piston 1, the auxiliary piston 2 moves with it and compresses the charge in the chamber 8, and finally a point is reached when the valve 12 will open and the compressed charge will be automatically transferred from the chamber 8 to the chamber 40 3. The igniting device then fires the charge which imparts a power stroke to the piston 1, while the auxiliary piston is cushioned by the compressed air in the chamber 18 and 45 the gas entrapped in the chamber 8.

In Fig. 2 the ports 4 and 9 are connected in communication by a valveless conduit 20, through which the charge compressed in

the chamber 8 will pass to the explosion chamber when the auxiliary piston 2 uncovers the port 4 on the up or instroke of such piston. 50

From the foregoing description taken in connection with the accompanying drawing, the advantages of the invention will be 55 readily understood by those skilled in the art, but it is to be understood that the construction shown is merely illustrative and that such changes may be made, when desired, as are within the scope of the 60 appended claim.

Having described my invention, what I claim and desire to secure by Letters-Patent, is:

The herein described internal combustion 65 engine, comprising a piston for receiving a power impulse, said piston having a central pocket in its inner end, an auxiliary piston opposed to the inner end of the power piston and having an outwardly extending central stem of a size in cross-section to snugly fit in said pocket and also having an inwardly extending central plunger, and a cylinder in which said pistons are movable rectilinearly; said cylinder having an ex- 75 haust port arranged to be uncovered by the power piston at the completion of the outward stroke thereof and also having a port for leading explosive mixture into the chamber between the auxiliary piston and the 80 cylinder head, and a passage for leading explosive mixture from said chamber to the chamber between the pistons, and further having on the cylinder head a tubular neck that receives the plunger on the auxiliary 85 piston and terminates in a closed chamber and is provided at a point adjacent the cylinder head with a port.

In testimony whereof I have hereunto set my hand in presence of two subscribing wit- 90 nesses.

CLARENCE C. LONGARD.
